STEAMING IMPLEMENT

Eugen Voigt, Bad Blankenburg (Thur. Wald.),
Germany, assignor, by mesne assignments, of
nineteen-twentieths to Albert C. Voigt, and
one-twentieth to John M. C. Willin, Jr., both
of Wicomico County, Maryland

Application July 14, 1937, Serial No. 153,609
In Germany July 28, 1938

2 Claims. (Cl. 68—222)

My invention relates to improvements in steaming implements for use in tailoring establishments, or the like, for napping cloth, removing sheen therefrom, and in similar capacities.

5 The invention is designed with the particular end in view of providing an efficient inexpensive device of this character equipped for generating and spraying a hot, dry steam against either garments suspended on hangers, or the like, or against cloths laid out in a flat condition.

10 Another object is the provision of an implement of this character designed particularly for easy effective manipulation to spray parts of garments, on hangers, not readily accessible to 15 present day devices of this class.

15 Other objects are also comprehended by my invention all of which, together with the exact nature of my improvement, will be readily understood when the following description and claims 20 are read with reference to the drawing accompanying and forming part of the specification.

In said drawing:

Figure 1 is a view partly in vertical section and partly in side elevation of a preferred form of my invention.

25 Figure 2 is a similar fragmentary view illustrating the implement tilted forwardly, and

30 Figure 3 is a view in vertical longitudinal section, drawn to an enlarged scale, as compared 35 with Figure 2, of a nozzle assembly forming part of the implement.

35 Describing my invention in detail, with reference to the drawing by numerals, in the embodiment thereof shown in Figures 1 to 3, the implement comprises as its basic element, a boiler or steam generating unit, having the form, preferably, of a cylinder 1 of suitable metal provided with an open bottom end 2 and a closed dome-shaped top end 3. Adjacent its bottom end the cylinder 1 is divided by a diametrical partition 4 forming a lower open compartment 5 and an upper, larger and closed compartment 6 in said cylinder. Suitably secured to the underside of the partition 4, as by a screw 1, to be housed in the compartment 5, is an electrical heating unit 8, of the well known hot plate type, and including binding posts 9 wired as by leads 10 and 11 to a contact plug 12 suitably secured in the wall of the cylinder 1, and for connection of the unit 8 to the house circuit as by the usual plug-in flexible connection not shown. The upper compartment 6 is the water container, the water being introduced thereto by way of a filler neck 13 extending from the top end 3 and exteriorly 45 threaded to receive a closure cap 14. The filler

neck 13 is located near the edge of the top end 3 to function in another capacity as will presently more clearly appear. Adjacent the top end 3 the cylinder 1 is divided by a diametrical perforated partition 15 functioning as a baffle preventing water from being drawn upwardly there-through with the steam rising in the top end of said cylinder.

50 Suitably secured to the underside of the top end 3 diametrically thereof is a steam discharge pipe 16 curved in conformity with the curvature of said end. One end of said pipe 16 is spaced slightly from the wall of the cylinder 1 to permit steam from the compartment 6 to enter said pipe and the other end of the pipe is extended out of the cylinder 1, for a short distance, and formed into an upwardly inclined, exteriorly threaded nipple 17. As will be understood a water-tight joint is formed between the nipple 17 and cylinder 1. Extending from the nipple 17, laterally of the cylinder 1, is an upwardly inclined nozzle assembly 18 comprising a pipe-like shank 19 detachably secured to said nipple 17 by means of a flange 20 on the inner end of said shank and a coupling 21 threaded on to said nipple. Extending from the opposite end of the shank 19, in depending relation thereto, is a cylindrical nozzle member 22 of relatively larger diameter than said shank and having closed, flat front and rear ends 23 and 24, respectively. The front end 23 is perforated, as at 25, to permit steam to escape therethrough. At its rear end, and diametrically opposite the shank 19, the nozzle member 22 has formed thereon integrally therewith a drum-like condensation trap member 26 depending from said rear end. An aperture 27 provided between said nozzle member 22 and trap member 26 establishes communication between said members. Within the nozzle member 22 is a deflector 22' curving from the discharge end of the shank 19 downwardly and rearwardly and terminating adjacent said aperture 27, said deflector serving to direct the steam away from the front end 23 of the nozzle and moisture therein into the receptacle 26, the deflector, in this instance, having the form of a short length of curved pipe open at its rear side as at 22. The front end 23 of the nozzle member 22 is oblique to the axis of said member 22 to facilitate opposing the same substantially flat, 55 in a vertical plane, against cloth hanging on a hanger, and underneath arms, collars, and other inaccessible places and without materially tilting the cylinder 1. The implement is designed to be manipulated over the clothes and tilted, as oc-

casion may require, and for this purpose is provided with a handle 28, preferably of horseshoe form, secured at one end, as at 29, to the cylinder 1 adjacent the bottom end thereof, and to the top end 3, as at 30, adjacent the nipple 17. The handle 28 curves up from the side of the cylinder opposite nipple 17 over the top end of said cylinder. As will be clear, the described form and arrangement of the handle 28 provides a bail by means of which the implement may be carried in suspended vertical position or manipulated readily to tilt the same.

In the use of the described form of the invention the compartment 6 is filled with water, by way of the neck 13 to a level slightly below the partition 15 so that the steam generated in said compartment passes in the untilted position of the implement through said partition for the purpose previously described. The steam 20 rising in the cylinder 1 escapes through the inlet end of the discharge pipe 16 into the nozzle assembly 18 as will be clear. The device is manipulated to move the nozzle member 22 over the clothes, and tilted to correspondingly tilt the 25 front end 23 of said nozzle to vary the angular relation thereof to the clothes as expediency may require. In this connection, it is to be noted that the implement may be tilted in a direction to tilt the nozzle assembly 18 downwardly at substantially any angle from the vertical, within a range of 90 degrees, without water entering the inlet end of the discharge pipe 16. Thus said 30 discharge pipe, under such conditions, forms in effect a trap, or by-path, for the steam by-passing the same around the water. This feature is an 35 important factor in keeping the steam issuing from the nozzle member 22 dry as will be manifest. The condensation trap member 26 is likewise an important factor in keeping the steam

dry since all condensation accumulating in the nozzle assembly 18 is trapped therein, and also that accumulating in the discharge pipe 16, in the forwardly tilted position of the implement.

The invention will, it is believed, be clearly understood from the foregoing description thereof without further explanation.

Manifestly the invention as described is susceptible of modification in other ways than set forth herein and right is reserved to all such modifications falling within the scope of the claims appended hereto.

What is claimed is:

1. A nozzle assembly comprising a cylindrical nozzle member having a perforated front end oblique to the axis of said member, a tubular shank extending from the opposite end of said member on one side of the axis thereof, the axes of said member and shank being parallel, and a drum-like condensation receptacle extending from said member adjacent said opposite end thereof diametrically opposite said shank, said member opening into said receptacle, and said shank being constructed and arranged to deliver steam to said opening.

2. A nozzle assembly comprising a cylindrical nozzle member having a perforated front end oblique to the axis of said member, a tubular shank extending from the opposite end of said member on one side of the axis thereof for delivering steam to said member, the axes of said member and shank being parallel, a drum-like condensation receptacle extending from said member adjacent said opposite end thereof diametrically opposite said shank, the member opening into the receptacle, and a deflector extending from the discharge end of said shank and curving therefrom toward said opening.

EUGEN VOIGT.
